UNITED STATES PATENT OFFICE.

JOHN E. MCGRANER, OF HARRISBURG, ILLINOIS, ASSIGNOR OF ONE-THIRD TO MARVIN
BRADSHAW AND ONE-THIRD TO ROY BRADSHAW, OF HARRISBURG, ILLINOIS.

RAIL-CLAMPING DEVICE.

Application filed March 21, 1924. Serial No. 700,846.

To all whom it may concern:

Be it known that I, JOHN E. MCGRANER, a citizen of the United States, residing at Harrisburg, in the county of Saline and

5 State of Illinois, have invented certain new and useful Improvements in Rail-Clamping Devices, of which the following is a specification, reference being had therein to the accompanying drawings.

10 This invention relates to a rail clamping device, and the object of the invention is the construction of an apparatus whereby an extension of a track in a mine can be quickly and efficiently accomplished.

15 Another object of the invention is the construction of an apparatus employing filler members constituting tracks, together with clamping elements cooperating with the filler members in the construction on an ex-
20 tension of a track.

With these and other objects in view, my invention comprises certain novel combinations, constructions and arrangements as will be hereinafter described, illustrated in
25 the accompanying drawings, and more particularly pointed out in the appended claims.

In the drawings:

Figure 1 is a perspective view of an apparatus constructed in accordance with the
30 present invention.

Figure 2 is a sectional view, taken on line 2-2, Fig. 1, and looking in the direction of the arrows.

Figure 3 is a perspective view of the primary jaw of the apparatus, while

Figure 4 is a perspective view of the auxiliary jaw.

Figure 5 is an enlarged, fragmentary view of the apparatus.

40 Referring to the drawings by numerals, 1 designates the ties and 2 is an ordinary rail resting upon one of the ties 1.

In constructing an extension of a track, for instance in a coal mine, I employ two of
45 my apparatuses but as they are duplicate in construction it will only be necessary to specifically describe one. When the coal has been mined beyond the end of the rail 2 and it is desired to get the coal cars close to the
50 mined coal or ore, as the case may be, I place one filler member 3 on a tie 1 with a strong, small head 4 resting under the tread of the rail 2; head resting flat against the web of the rail. The filler member 3 is provided
55 with a web 5 and a broad base 6, which base

6 is provided with a flat, outer surface 7 that bears snug against the flat bearing face 8 of the auxiliary jaw 9 (Figs. 2 and 4).

The rail 2 rests upon the flat face 10 of the primary jaw 11, and this jaw 11 is provided with a pointed bearing portion 12 bridging over the base of rail 2 (Figs. 1 and 2) and bearing against the web of said rail; it is to be noted that the center of pressure is caused upon the web of the rail right at the middle of the head 4 of the filler member 3, thereby making a very steady and secure structure, for locking the parts 2 and 3 together, so that this "extension" of the roadway in the mine will be secure and not liable to become disassembled, whereby delays and loss in mining of coal and other minerals will be eliminated.

The auxiliary jaw 9 is provided with a horizontal, threaded aperture 13 that receives the bolt 14, which bolt also extends through aperture 15, of the primary jaw 11. A suitable operating wrench 16 may be placed on the head 17, of bolt 14, and any type of an operating pin, for turning a bolt, 70 may be placed in the aperture 18, of head 17.

A horizontal, conical socket 19 is formed in the body of the auxiliary jaw 9, above aperture 13, and this socket 19 receives the conical wedge pin 20, which pin is integral with the inner end of the body of the primary jaw 11. This wedge pin 20 assists in assembling the apparatus before the bolt 14 is inserted, since the two jaws can be placed together, with pin 20 entering socket 19, 85 and as the bolt is threaded through the jaws the pin will be wedged in the socket further assisting in producing a very strong and efficient assembling of the parts of my apparatus.

The filler members 3 of my apparatus will act as rails for receiving the wheels of the car, or cars, from the rails 2, so that the cars to be loaded can be brought up very close to the material that the cars are to be loaded with; the flanges of the car wheels traveling over the webs 5 of the filler member 3.

My apparatus eliminates the use of spikes or nails, in assembling parts for producing an extension of a roadway, which is a great saving to the mine owner.

While I have described the preferred embodiment of my invention, and have illustrated the same in the accompanying drawings, certain minor changes or alterations

may appear to one skilled in the art to which this invention relates, during the extensive manufacture of the same and I, therefore, reserve the right to make such alterations or changes as shall fairly fall within the scope of the appended claims.

What I claim is:

1. In an apparatus of the class described, the combination of a primary and an auxiliary jaw, said auxiliary jaw provided with a cone-like socket, said primary jaw provided with a cone-like wedge adapted to enter said socket, means for drawing the jaws together and holding the same in an assembled position, and a filler member assembled with said jaws.
2. In an apparatus of the class described, the combination with a rail provided with a web and a base, an auxiliary jaw contiguous to said rail, of a primary jaw under said base, said primary jaw provided with a

pointed bridging portion extending over the base of the rail and pressing against approximately the center of the web, a filler member provided with a broad base bearing against the auxiliary jaw, said filler member provided with a web and with a small head having a flat outer face bearing against the web of the rail with the pressure exerted by the pointed portion of the primary jaw in approximately the middle of said head, manually-operated rotatable means in said jaws for drawing the same together and holding them in their assembled position, and a socket and pin structure formed upon said jaws for assisting in assembling and holding the jaws together, substantially as shown and described.

In testimony whereof I hereunto affix my signature.

JOHN E. McGRANER.
